ANGUS McKAY, OF GRETNA, LOUISIANA, ASSIGNOR OF ONE-HALF TO
GEORGE W. McKAY, OF DETROIT, MICHIGAN.

DESIGN FOR A TABLE.

No. 37,568.

Specification for Design.

Registered Oct. 3, 1905.

Application filed July 22, 1905. Serial No. 270,879. Term of patent 7 years.

To all whom it may concern:

Be it known that I, ANGUS McKAY, a citizen of the United States, and a resident of Gretna, in the parish of Jefferson and State of Louisiana, have invented a new, original and ornamental Design for a Table, reference being had to the accompanying drawing, in which the figure is a perspective view of a table, showing my design.

I claim—

The ornamental design for a table as shown.

ANGUS McKAY.
